Attorney.

UNITED STATES PATENT OFFICE.

JOSEPH F. WOOLDRIGE, OF RICHMOND, VIRGINIA.

DESIGN FOR PLUG-TOBACCO.

SPECIFICATION forming part of Design No. 12,521, dated October 11, 1881.

Application filed July 11, 1881. Term of patent 3½ years.

To all whom it may concern:

Be it known that I, JOSEPH FLOOD WOOLDRIGE, a citizen of the United States, residing at the city of Richmond, in the county of Henrico, and State of Virginia, have originated and invented a new and useful Design for Plug-Tobacco; and I do hereby declare that the following is a full, clear, and exact description thereof, reference being had to the accompanying drawing, forming a part of this specification.

Referring to the annexed drawing, which clearly illustrates the nature of my design, A designates the tobacco rope, which commences at a, and is bent around substantially in the form of a horseshoe. The ends b, after the horseshoe has been formed, are bent up and against the inner sides of the horseshoe and against each other, the rope A, when thus bent,

being compressed together or against its contracting sides. 20

If desired, a web, c, of tobacco may be wrapped around the ends b, to hold them together.

What I claim is—

A design for plug-tobacco, composed of the tobacco rope A, bent in the form of a horseshoe, and having its ends b bent up against the inner sides of the shoe, substantially as shown and set forth. 25

In testimony that I claim the foregoing as my own I affix my signature in presence of two witnesses.

JOSEPH FLOOD WOOLDRIGE. 30
